UNITED STATES PATENT OFFICE.

DANIEL HUTCHINSON, OF POLAND, MAINE.

BREECHING FOR VEHICLES.

SPECIFICATION forming part of Letters Patent No. 296,694, dated April 8, 1884.

Application filed February 4, 1884. (No model.)

To all whom it may concern:

Be it known that I, DANIEL HUTCHINSON, a citizen of the United States, residing at Poland, in the county of Androscoggin and State of Maine, have invented certain new and useful Improvements in Holdbacks or Breechings, of which the following is a specification.

My invention relates to an improved holdback or breeching in which the breeching-strap, instead of being attached to the harness, is fastened to a device upon the wagon-shafts; and the objects of my improvements are, first, to do away with the crupper, back-strap, and breeching-straps of a harness, thereby making less work to harness a horse; second, to leave the muscles of the horse free to act, thereby getting greater speed and greater ease of traveling; and, third, to avoid accidents by the breeching catching in the holdback—a common occurrence when the old breeching is used. I attain these objects by the mechanism illustrated in the accompanying drawings, in which—

Figure 1 is a top view of the entire device; Fig. 2, a detailed view in perspective of the breeching-strap and the devices upon the shafts to which it is fastened; Fig. 3, a view of one of the devices upon the shafts to which the breeching-strap is attached.

Similar letters refer to similar parts throughout the several views.

The breeching-strap *b* reaches from shaft to shaft, and is buckled into the holdback *f*, which is turned up on the end of the spring *c*, referred to hereinafter. The standard *e* passes through the piece of metal *h*, which is fastened to the under side of the shaft *a*. The standard *e* has a thread cut upon it, and is to regulate the height of the breeching-strap *b*, and is held at its proper height by means of nuts

above and below the piece of metal *h*. It (the standard *e*) is enlarged into a clasp at its upper end, through which the spring *c* passes. (See Fig. 3.) This spring *c* is a flat piece of spring-steel, one end of which is fastened flatwise upon the shaft *a* by the clasp *g*. The other end passes the clasp upon the standard *e*, and is turned up into the holdback *f*, as shown in Fig. 3. The spring *c* should be made sufficiently stiff to act as a brace upon the standard *e*, and yet spring down or up, as the standard is lowered or raised.

d is a small spiral spring, one end of which is fastened around the standard *e*, between the nuts *i*, the other end being riveted to the breeching-strap *b*. The object of the spiral spring *d* is to prevent the breeching-strap *b* from sagging, and at the same time keep it snug to the horse.

Having fully described my invention, what I desire to claim and secure by Letters Patent is—

1. In an improved breeching, the combination of the breeching-strap, *b*, which is buckled into the holdback *f*, with the spring *c* and the standard *e*, substantially as shown, and for the purposes specified.

2. The combination, in an improved breeching, of the spring *c*, having one end turned up into the holdback *f*, with the standard *e* and the shaft *a*, substantially as set forth.

3. The combination, in an improved breeching, of the spring *d*, having one end secured to the standard *e*, with the breeching-strap *b*, substantially as described, and for the purposes specified.

DANIEL HUTCHINSON.
